(57) **CLAIM**

The ornamental design for a videoscope display, as shown and described.

DESCRIPTION

FIG. 1 is a front-right-top perspective view of a videoscope display embodying the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front elevational view thereof, including an illustration of an example of a handset and probe which may be coupled in a wired or wireless fashion to the videoscope display.

The broken lines in the figures illustrate portions of the videoscope display and environmental matter and form no part of the claimed design.
